UNITED STATES PATENT OFFICE.

CHARLES M. SHEPPERSON, OF OMAHA, NEBRASKA.

RECEPTACLE ATTACHMENT.

1,179,566.

Specification of Letters Patent. Patented Apr. 18, 1916.

Application filed April 6, 1915. Serial No. 19,433.

To all whom it may concern:

Be it known that I, CHARLES M. SHEPPERSON, a citizen of the United States, residing at Omaha, in the county of Douglas and 5 State of Nebraska, have invented certain new and useful Improvements in Receptacle Attachments, of which the following is a specification, reference being had therein to the accompanying drawing.

10 This invention relates to improvements in receptacle attachments for down legs or spouts, and although capable of service in a variety of connections, is particularly designed for and serviceable in connection 15 with toilet apparatus involving the use of portable bowls, as in the case of railroad service where it is obviously desirable that the apparatus be capable of its normal use at all times, while obviating the objections 20 flowing from the discharge of waste or refuse in stations or populated localities.

That the invention may be better understood I will herein disclose the preferred embodiment of the same, said embodiment 25 comprising a receptacle of convenient size and shape, adapted to be connected in communication with a down-spout or discharge pipe and being provided with an open bottom adapted to be closed by a door or 30 equivalent cover of improved type associated with improved mechanism for effecting the operation and closing thereof.

The details in the construction and arrangement of parts of the device will be 35 apparent from the specific description hereinafter contained, when read in connection with the accompanying drawings forming part hereof.

In the drawings: Figure 1 is a fragmentary vertical sectional view of a suitable support, such as the body of a car, having the improved apparatus installed therein; Fig. 2 is a vertical sectional view through the attachment; Fig. 3 is a top plan view of 45 the receptacle; Fig. 4 is a vertical sectional view through the attachment taken at right angles to the section on which Fig. 2 is taken.

Referring more specifically to the drawings wherein like reference characters designate the same parts in the several views, A represents the down-spout or discharge pipe of any type of bowl or other apparatus in connection with which the invention may be 55 employed, the pipe extending through the

car floor B and for a suitable distance therebelow to enable fastening of the receptacle attachment thereto.

C indicates the receptacle, in this instance of elongated rectangular outline, although 60 it may be of any other contour desired, the same having a neck portion D, adapted to be suitably coupled to the pipe A, to afford communication of said pipe with the interior of the receptacle. The bottom of the 65 receptacle is tapered downwardly interiorly thereof, as at E, to a discharge opening F; and for normally preventing discharge through said opening, and temporarily maintaining the receptacle contents therein, 70 I provide a suitable closure, in this instance in the nature of a door G, hinged at one edge, as at H, to one of the lower edges of the receptacle. The receptacle and lower door is preferably formed of metal to give 75 the same the permanence, weight and strength desired.

In order to seal the bottom of the receptacle, the door is formed hollow and with overhanging flanges J, so as to receive on 80 the interior thereof and be confined in place by said flanges, a rubber or other packing pad K, the central portion of the pad being held in place by means of a plate L, secured by detachable rivets or screws M passing 85 through the pad K, and the bottom of the door G, to anchor the clamping plate L to said bottom. This arrangement affords a practical means for removably securing the sealing pads in place while presenting at 90 all times the continuous exposed sealing ring or portion N, the latter being adapted to be pressed against the depending edge O of a continuous ring or flange P, entirely 95 surrounding and immediately bordering the discharge opening F at the lower end of the receptacle.

To not only close the door or cover G with reference to the opening F, but also to force the flange P into the embedded and 100 sealing relation to the rubber pad K, I provide a pair of links Q, arranged along the opposite sides of the receptacle C, the said links being pivoted at their lower ends to the forward or free ends of the door or closure, as at R, and passing upwardly and diagonally across the sides of the receptacle, through elongated guiding loops S, projecting rearwardly from and rigidly attached to the receptacle, so that the projecting upper 110

ends of the links are pivotally connected, as at T, to a vertically disposed reciprocally operating rod U, provided with an outwardly turned operating handle W.

5 From the foregoing description it will be instantly appreciated that the handled rod U being free, the weight of the door G and links Q, operatively associated therewith, will cause the door to fall by gravity into 10 the open position, as indicated in the dotted lines Fig. 2, the length of the loops S affording sufficient freedom for the necessary movement of the links. On the other hand, the drawing upwardly of the handle W, through the connected rod U and links Q effects the closing and sealing of the door; and the parts may be secured in this position for the desired period of time by a manually operable clamping screw or other 15 fastener, represented at X, and coöperating with a guide bracket Y on the wall to which the guide bracket is attached, to bind the reciprocal rod U against movement.

20 The connection between the links Q and the rod U is through the medium of a rock shaft 5 pivotally mounted at its opposite ends 6, to constitute the pivotal connections T, and pivotally connected intermediate of its ends at 7 to the bifurcated lower end of 25 the rod U. By this connecting arrangement, sufficient flexibility of the operating parts is afforded to allow for any irregularities in the formation of the parts or slight dis- 30 arrangements thereof within reasonable 35 limits, under ordinary working conditions.

8 are small upwardly extending, in- 40 teriorly arranged pipes, screened at their lower ends—and turned outwardly at their upper portions through the front and rear 45 walls of the receptacle, where they are pro- 50 vided with down-turned discharge terminals 10, the purpose of these pipes being to enable liquid contents to overflow in instances where the receptacle is nearly full. The 55 disposition of the terminals at the front and rear prevents interference thereof with the movable links at the sides of the receptacle, as will be readily understood.

While I have herein disclosed one special 50 embodiment of the invention, it will be ap- 55 parent to persons skilled in the art that the invention is capable of embodiment in still other forms and devices, as may be in keeping with the spirit and scope of the hereto appended claims.

Copies of this patent may be obtained for five cents each, by addressing the "Commissioner of Patents, Washington, D. C."

Having thus described the invention, what is claimed is:

1. An apparatus of the character de- 60 scribed, comprising a receptacle having an upper coupling portion and a lower dis- 65 charge end, the walls of the receptacle being spaced apart a uniform distance throughout its length, an integral inclining member di- 70 rected interiorly from the walls of the re- 75 ceptacle and leading to a relatively small discharge pipe extending to the bottom or lower portion of the receptacle and entirely surrounded by and spaced a substantial dis- 80 tance from the walls thereof, and a cover hinged to the receptacle at its lower end and 85 extending entirely thereacross to form a closure for the relatively small discharge pipe therein and the lower end of the re- 90 ceptacle.

2. An apparatus of the character de- 75 scribed, comprising a receptacle of rectangu- 80 lar formation having an upper coupling portion and a lower discharge end, the dis- 85 charge end of the receptacle being provided with an integral inwardly inclining portion 90 having a downwardly projecting relatively small outlet pipe leading to a point near the discharge end of the receptacle, the said outlet pipe being spaced from the walls of the receptacle and entirely surrounded by the 95 said walls whereby the discharge pipe is pro- 100 tected, and a cover hinged to the receptacle and extending entirely thereacross to form a closure for the outlet pipe and the lower end of the receptacle.

3. An apparatus of the character de- 95 scribed, comprising a receptacle having ver- 100 tically extending walls, a member directed interiorly from the walls thereof and leading to a relatively small discharge pipe ex- 105 tending to the lower portion of the said re- ceptacle and entirely surrounded by and spaced from the walls thereof whereby the discharge pipe is entirely surrounded and protected, and a cover hinged to the recep- 110 tacle at its lower end and extending there- across to form a closure for the relatively small discharge pipe therein.

In testimony whereof I hereunto affix my signature in the presence of two witnesses. 105

CHARLES M. SHEPPERSON.
